UNITED STATES PATENT OFFICE.

JOHN M. COLBERT, OF MANTUA, ASSIGNOR TO JAMES H. FERGUSON AND
FRANK FERGUSON, OF BRIDGETON, NEW JERSEY.

CAN-SOLDERING MACHINE.

SPECIFICATION forming part of Letters Patent No. 399,020, dated March 5, 1889.

Application filed January 22, 1889. Serial No. 297,191. (No model.)

To all whom it may concern:

Be it known that I, JOHN M. COLBERT, a citizen of the United States, residing at Mantua, Gloucester county, New Jersey, have invented certain new and useful Improvements 5 in Machinery for Soldering the Tops of Tin Cans, of which the following is a full, clear, and exact specification.

My invention relates to machines for soldering the tops upon sheet-metal cans, and especially to that class in which revolving soldering-irons are employed; and my invention consists of a head for such machines embodying a series of vertical spindles having 15 pinions driven from a single revolving gear and carrying soldering-irons, and otherwise constructed, as fully set forth hereinafter, and as illustrated in the accompanying drawings, in which—

20 Figure 1 is a plan view of a soldering-head embodying my improvements. Fig. 2 is a sectional elevation of the said head. Fig. 3 is a plan illustrating a modification of the driving-gear.

25 The head A may be a box, case, or frame of any suitable form and construction to support a series of spindles, 1, to each of which at the lower end is secured a soldering-iron, 2, provided at its lower end with an annular 30 soldering-ring, 3. As shown, the head is in the form of a case having a cylindrical rim or body, 4, projecting above a flat top, 5, to form an annular guide, 6, and projecting below a flat bottom or partition, 8, to form a dependent annular flange, 9. Each spindle 1 passes through an opening in the top 5, and carries a pinion, 10, and all the spindles are arranged in a circle, so that all of the pinions 35

40 will gear with the teeth of a deep annular rack or gear-wheel, 12, which lies upon the top 5 and is maintained in position thereon by the guide 6. Each of the irons 2 passes through an opening, 13, in the bottom 8, projecting to such an extent as to be guided by 45 said bottom, whatever may be the height to which the iron is raised. The irons are heated in any suitable manner common to this class of apparatus, as by gas-jets, &c., which are not shown, as they constitute no part of my 50 present invention, and the annular gear-wheel

12 is driven from any suitable source of power and through any suitable mechanism, and as it revolves it imparts motion to all of pinions 10 and the irons connected therewith. One mode of driving the wheel 12 is illustrated, 55 the same consisting of a guide-wheel, 13, upon a shaft, 14, turning in a stationary support and provided with a grooved pulley, 15, receiving a driving-belt, 16.

It will be noted that the driving-wheel 12 60 is much deeper than the pinions 10, and that the shafts and irons are so supported and suspended in the head as to be capable of a vertical movement. This permits the head to be lowered to bring the irons in contact with a 65 series of cans, (shown in dotted lines,) and also permits each iron to accommodate itself to the height of the can below it without the pinions 10 being disengaged from gear with the wheel. By this arrangement of deep driving-gear and iron supporting-shafts provided 70 with pinions and capable of vertical movements independent of the driving-gear it is possible to move the entire head vertically to bring the irons on the cans, while the irons 75 adjust themselves to the inequalities in the heights of the cans.

By the use of a single driving-wheel gearing with a series of pinions each connected with one of the irons I am enabled to rotate all 80 the irons together, either continuously in one direction or to impart a reciprocating rotary motion thereto from a single driving-shaft.

The driving-wheel 12 may be in the form of an ordinary toothed wheel instead of being 85 annular. In such case, however, it will be arranged within the circle of pinions 10, as shown in Fig. 3.

In that class of machines in which the head is to remain fixed it will not, of course, be necessary in all cases to provide a driver-wheel of greater depth than the pinions, and only sufficient vertical movement or play of the spindles and irons need be permitted to enable the irons to accommodate themselves to inequalities in the cans. 90

By extending the flange 9 below the bottom 8 I form a guard inclosing the lower end of the irons, which protects them from air-currents and tends to prevent their rapid cooling. 100

Without limiting myself to the precise construction and arrangements of parts shown, I claim—

1. A head for a can-soldering machine, consisting of a case or frame, a series of spindles supported therein and provided with soldering-irons and pinions, and a driving-wheel gearing with all the said pinions, substantially as set forth.
- 10 2. The combination, in a head of a can-soldering machine, of a support for a series of vertical spindles arranged in a circle and each provided with a pinion and a soldering-iron, and a driving-wheel gearing with all of said pinions, substantially as set forth.
- 15 3. The combination of a frame or case having bearings for a series of spindles arranged in a circle and each capable of moving vertically in its bearings, a pinion, and a soldering-iron carried by each spindle, and a driving-wheel gearing with all of the pinions and greater in depth than the latter, substantially as set forth.

4. The combination, in a head of a can-soldering machine, of a case supporting a series of vertical spindles, a series of soldering-irons carried by the spindles, the case extending below the irons, and pinions upon the spindles gearing with the driving-wheel, substantially as set forth.

5. The combination of a case provided with a perforated top and bottom, a series of vertical spindles extending through the perforations in the top and each provided with a pinion at its upper end gearing with a driving-wheel, and a series of soldering-irons carried by the spindles and each extending through one of the perforations in the bottom of the case, substantially as set forth.

In testimony whereof I have signed my name to this specification in the presence of two subscribing witnesses.

JOHN M. COLBERT.
